UNITED STATES PATENT OFFICE.

DAVID F. FELMLY, OF AKRON, OHIO, ADMINISTRATOR OF WILLIAM DUERR, DECEASED,
ASSIGNOR OF ONE-HALF TO CHRISTANA M. DUERR AND ONE-HALF TO THOMAS PHILLIPS,
OF CUYAHOGA FALLS, OHIO.

CLUTCH-PULLEY.

No. 901,603.

Specification of Letters Patent.

Patented Oct. 20, 1908.

Application filed May 6, 1907, Serial No. 372,286. Renewed March 5, 1908. Serial No. 419,395.

To all whom it may concern:

Be it known that WILLIAM DUERR, late a citizen of the United States, deceased, and resident of Cuyahoga Falls, in the county of 5 Summit and State of Ohio, in his lifetime invented certain new and useful Improvements in Clutch-Pulleys, of which the following is a specification.

This invention relates to clutches, and has 10 for its object to provide a device of this kind, which will be simple, strong, and efficient.

In the accompanying drawings, which illustrate the invention,—Figure 1 is a broken end elevation of the clutch; Fig. 2 is a 15 side elevation, partly in section; Fig. 3 is a broken detail view; Fig. 4 is a perspective view of one of the clutch members.

Referring more particularly to the drawings, 1 indicates one of the clutch members 20 which is provided with a rim or flange 2, and is adapted to be rigidly secured to the shaft 3 in any desired manner, as by a set screw 4. The loose member of the clutch comprises a 25 hub or hollow member 5, which is recessed at one end, as shown at 6, and provided with a flange 7, which is adapted to stand adjacent to the edge of the flange 2.

The face of the flange 7 is provided with 30 radially arranged grooves 8, within which are reciprocally mounted the arms 9 of the clutch members 10 and 11. Said clutch members are preferably arranged upon opposite sides of the flange 2 and each comprises a segmental portion which is preferably provided 35 with a shoe or wearing plate 12, the plates upon the inner shoes being placed upon the outer face thereof, and those upon the outer shoes being placed upon the inner face. Strengthening ribs 13 extend from the 40 arm toward the free edges of the clamps or segmental portions 10 and 12, and the ends of said clamps may be provided with ribs 14 to assist in holding the wearing plates.

An annular plate 15 is secured to the face 45 of the flange 7 so as to hold the arms 9 in their respective recesses 8 and the inner end of each arm 9 is provided with a head 16, which is adapted to fit in one of the recesses 17 formed in the periphery of a sleeve 18, said 50 sleeve being reciprocally mounted in the hollow or hub 5. The recesses 17 have their walls dove-tailed or inclined forward so as to engage with the inclined walls of the heads 16, and the bottom of each recess is inclined 55 from one end to the other relatively to the

axis of the clutch or shaft upon which it is mounted. The inclination of said bottoms are arranged in opposite directions and the overhanging or dovetailed walls are similarly inclined or formed to correspond therewith so that when the sleeve is moved in one direction, part of the clutch members will be moved outward and the other ones drawn inward, thereby causing said members to engage with the opposite sides of the rim 2, 60 as heretofore described. By providing the clutch with six movable members, alternating them as shown in the drawings, each outwardly moving member will engage with said rim between two inwardly moving members, and each inwardly moving member will engage with the outside of said rim between two outwardly moving members, thereby 65 causing a uniform pressure upon the rim, and by making said members of a sufficient 70 length they will engage with the rim, substantially entirely therearound, except at short distances between the ends of adjacent members, and by making said members of sufficient width, a very great bearing surface 75 is secured for locking the two members of the clutch together.

The hub or collar 5 is provided with longitudinally arranged perforations 19, through which screw-threaded pins 20 project, and when the clutch is to be used upon two aligned shafts as in the present instance, the collar is rigidly secured to the shaft 21 by means of a set screw 22. The inner ends of the pins or stems 20 are screwed into the inner end 90 of the sleeve 18 and are adjustably connected at their outer ends with a shifting collar 22, as by being passed through perforations in a flange 23 and secured by means of nuts 24 upon opposite sides of said flange. The opposite end of the collar is provided with an annularly recessed head or enlargement 25, within which is seated a band 26, having trunnions 27 arranged at diametrically opposite points for engagement with the shifting lever 28. The band 26 is preferably formed from two semicircular pieces, each of which is provided with one of the trunnions 27 and has laterally extended projections 29, which are adapted to be secured together by a bolt or screw 30. The inner faces of said projections are cut away, as shown at 31, which will permit of the projections being moved toward each other to compensate for wear by simply grinding off a 110

small portion of the contacting portions of said projections.

As above described, it will be seen that the clutch is composed of but few parts and these arranged in such a manner as to be positively operated, and a very large bearing surface is secured for binding the clutch members together. The clutch is so compact that it can be used to good advantage on such mechanisms as automobiles, etc., or it can be made of such size as to adapt it for use upon any other form of mechanism. When it is desired to use the clutch upon a single shaft, either one of the members can be rigidly secured thereto, and the other one provided with a transmitting member that will be adapted to take the place of the ordinary loose pulley.

Having described the invention, what is claimed is:—

- 20 1. In a clutch, two members, one of which is provided with a flange, and the other one is provided with a plurality of radially arranged reciprocatory arms, the outer end of each 25 arm being provided with a segmental clamp and the inner end provided with a head, and a reciprocatory sleeve having inclined dovetailed recesses in its periphery for the reception of said heads, said recesses being inclined 30 in opposite directions for causing said clamps to engage with said flange upon opposite sides thereof.
2. In a clutch, a member provided with a flange, a radially recessed member adjacent 35 to the edge of said flange, reciprocatory arms in said recesses, the outer ends of which are provided with clamps, an annular plate secured over said recesses, and a longitudinally recessed sleeve for engaging with said 40 arms and causing the alternate arms to be moved in opposite directions, whereby their

clamps are caused to simultaneously engage with said flange upon opposite sides thereof.

3. In a clutch, a member provided with a flange, a collar provided with a radially recessed flange adjacent to the rim of the first-mentioned flange, said collar being provided with a recess at one end and with longitudinal perforations communicating therewith, arms reciprocally mounted in said radial recesses, 45 and each provided at its outer end with a clamp for engaging with said first-mentioned flange, a sleeve reciprocally mounted in said recess having inclined recesses in its periphery for engaging with the inner ends of said 50 arms, screw threaded pins projecting through said perforations into said sleeve, and a shifting collar adjustably connected with the outer ends of said pins.

4. In a clutch, two members, one of which 60 is provided with means for detachably engaging with the other, a shifting collar for actuating said means, the outer end of said collar being provided with an annularly recessed head, a band on said head comprising two 65 semi-circular members, each of which is provided with a trunnion and has each end provided with a perforated projection, the inner face of said projection being cut away except at its tip, and means through said perforation 70 for holding the corresponding tips of the two members in contact.

In testimony whereof I have hereunto set my hand in the presence of two subscribing witnesses.

DAVID F. FELMLY,
*Administrator of the estate of William Duerr,
deceased.*
